LOUD SPEAKER

Henryk Brzeski, Warsaw, Poland

Application December 12, 1932, Serial No. 646,915
In Germany November 9, 1932

1 Claim. (Cl. 179—115.5)

The present invention relates to a loud speaker which is improved according to new observations on the nature of the operations involved in the loud speaker in the conversion of alternating currents over a considerable range of frequencies.

The invention is based on the fact that the sound emitted is considerably influenced by oscillations of very high frequency and small amplitude, which, however, can be distinguished by 10 the human hearing organs.

In the construction of loud speakers, this fact has hitherto not received sufficient attention. The loud speakers were so constructed that the magnetic field produced by the alternating current flowing through the moving coil was considerably effected by the Foucault eddy currents and by hysteresis, so that the energy of the oscillations of high frequency which influence the quality of the sound was almost entirely lost and 20 the production of a natural tone by the loud speaker was diminished.

In the known loud speakers the variable magnetic field due to the moving coil is formed along the line of the smallest magnetic resistance, that 25 is, through the homogeneous iron material of the magnets which produce the stationary magnetic field. In this material, on account of the action of the variable magnetic field of the moving coil, there are variations in polarity of the 30 molecules, as well as Foucault eddy currents which produce considerable losses in energy which is converted into heat. These losses are greater at higher frequencies.

The present invention consists in the use of 35 means whereby the energy losses, due to hysteresis and eddy currents, are diminished. In this way a great improvement in the clearness of the tones in reproduction of the human voice or of musical instruments is obtained.

40 One such means consists in the construction of the loud speaker with two diaphragms provided with coils wound in opposite directions so that the coils produce oppositely directed magnetic fields. The moving coils secured to the diaphragms (cones) are situated at the ends of the 45 magnet which produces a stationary magnetic field, the diaphragms being situated on a common geometrical axis and being oppositely directed. The magnetic fields produced by the coils are 50 oppositely directed and prevent the lines of magnetic force flowing through the mass of the stationary magnets or the continuous current electro-magnets.

This arrangement of the two oppositely directed moving coils also nullifies the effect of 55

variations in the exciting current when this consists, for example, of a badly rectified alternating current. The pulsations of such a current act on the two balls in opposite directions so that the resultant effect is zero.

A further means for diminishing the above-mentioned losses consists in making the surroundings of the alternating current coils highly permeable to the magnetic lines of force. With this object in view, especially the parts of the stationary magnets which are close to the moving coil consists of material which is highly permeable to the lines of magnetic force, for example permalloy, ferrocort or of thin insulated plates of such material. These parts of the stationary magnet may also consist of such materials in powdered form pressed together with insulating material, such as bakelite.

The magnetic current, due to the moving coils, flows for a short distance through the parts of the stationary magnets near the coil, the magnetic circuit being closed in a line close to the coil windings. The current loses none of its strength because no eddy currents can occur. The element on which the moving coil is wound may also be 70 constructed of a material which is highly permeable to the currents or it can be fitted with such material at the points where the magnetic current flows.

In order to avoid the occurrence of resonant 85 oscillations of the moving coils and the cones or diaphragms connected therewith, the cones are fitted with ends which damp the natural oscillations of the whole system. Some constructional forms of the invention are illustrated diagrammatically in the accompanying drawing.

Fig. 1 is an axial section through a loud speaker with stationary magnets.

Fig. 2 is an axial section through the coil and the magnet in a known construction.

Fig. 3 is an axial section through the coils and the magnet in the loud speaker according to the invention.

Fig. 4 shows a part of the section according to Fig. 1 on a larger scale.

Fig. 5 shows the same for another construction.

Figs. 6 and 7 show the connections for the coil windings.

Fig. 2 shows an electro-magnet having a continuous current coil 2 arranged on its iron core 1. 105 The magnetic currents *a* produced by the continuous current, flow through the mass 3 of the electro-magnet and intersect the moving coil 4 through which the alternating currents from the amplifier flow. The variable magnetic current 110

b excited by the moving coil 4, flows through the whole mass 3 and the iron core 1 of the electro-magnet because it remains at the points of smallest magnetic resistance. (The magnetic resistance of the air is a thousand times that of the iron). On account of the variable magnetic current b flowing through the iron, there are considerable losses due to hysteresis of the Foucault's eddy currents. This causes a distortion of the sound waves because in particular the energy of the high frequency oscillations is almost entirely converted into heat and can no longer act on the coil 4.

In the diagram shown in Fig. 3 of a loud speaker constructed according to the invention, two moving coils 4 are employed which are arranged symmetrically at both ends of the iron core 1 of the electro-magnet in such a manner that the windings of the coils 4 are in opposite directions. The variable magnetic currents b, due to these coils 4, are oppositely directed and prevent the magnetic lines flowing through the whole mass 3 of the electro-magnet because the magnetic currents b' flowing in opposite directions through this mass neutralize one another. On account of the difference in magnetic potential between the points A and B, the magnetic current takes the form of a line closely surrounding the winding of the coils 4.

In the vicinity of the windings of the moving coils a path of material of small magnetic resistance is provided for the alternating magnetic current b. This material consists of thin insulated plates or of a powder combined with insulating material. The magnetic field b is thus not distorted on account of the production of eddy currents and the losses due to hysteresis are reduced to a minimum.

In the constructional form shown in Fig. 1, a stationary magnet 5 is employed on the ends of which is arranged a disc-like ring 6 of iron which is separated by the copper ring 7 from the iron core 1. The ring 6 is secured to the chassis 8 by means of screws 9. On the chassis 8, by means of a ring 10, the diaphragm in the form of a cone 11 is secured which is provided with an end 12. On the cone 11 is a coil carrier 13 for the moving coil 4 which is arranged between the ends of the iron core 1 and the ring 6. In the iron ring 14 at the end of the iron core 1, small plates 15, for example of permalloy, are embedded. Similar small plates 16 are placed on the inner surface

of the ring 6. The coil carrier 13 for the moving coil 4 in the arrangement shown in Fig. 4 is made entirely of a material of very small magnetic resistance and according to Fig. 5 is provided with recesses 17 in the path of the variable current b which are filled with material of very small magnetic resistance.

The chassis 8 is provided with contacts 18 to which the leads carrying the modulated alternating current are attached. The contacts 18 are provided with springs 19 which press open the conducting pins 20 which carry the current to the conductor 21 which is insulated from the chassis 8 by means of rings 22 and 23. The ring 22 is connected with the cone ring 25 by radial arms 24, the cone ring 25 being secured to the end 12 of the cone 11 and to the coil carrier 13. The metallic conductor 21 is laid between the cone ring 25 and the cone 11 with its end 12 to the windings of the moving coil 4 (Fig. 4).

The moving coil 4 consists of several layers of winding which are wound in such a manner that there is a very small potential difference between the separate windings, that is, so that the current flows from the last winding of one layer to the first of the next layer. This causes a diminution of the direct flow of current between adjacent windings on account of capacity.

The windings of each moving coil 4 can also be divided into two parts 4' and 4'', the ends of which are connected by conductors 21 to contacts 18, 18' and 18''. In such a case, by arranging the coils 4 in parallel (Fig. 6), the potentials of the sections of the winding can be equalized by connecting the contacts 18' through the conductor 110 26 or by connecting the contacts 18'' with a conductor 27 as shown in Fig. 7, the coils 4 can be arranged in series. The connection of the coils 4 in series or parallel enables them to be adapted to the amplifier.

What I claim is:

A loud speaker comprising a field magnet system, pole pieces on the field magnets, a speech coil, a former on which the speech coil is wound, suspended between the pole pieces, and having recesses, insertions of material of small magnetic resistance in the recesses of the former, and insertions in the pole pieces of material of small magnetic resistance, for limiting the magnetic field due to the speech currents to a small space 125 around the speech coil.
